UNITED STATES PATENT OFFICE

LEONARD KEBLER, OF BRONXVILLE, NEW YORK, ASSIGNOR TO WARD LEONARD ELECTRIC COMPANY, A CORPORATION OF NEW YORK

RHEOSTAT

Application filed July 22, 1926. Serial No. 124,119.

This invention relates to rheostats having a series of contacts with adjustable means for controlling the resistance in the circuit as desired. It more particularly relates to regulating rheostats adapted to be mounted upon a panel-board or other suitable support.

One of the objects of this invention is to provide a rheostat construction formed of totally enclosed units adapted to be built up and added one to the other to provide a total number of units for securing the degree and character of control desired; and to accomplish this by a simple construction which may be utilized and assembled by the manufacturer or the subsequent user.

A further object is to provide a construction which is adapted to be mounted on the front or back of the panel-board without changing the construction so that the same device may be utilized for either character of mounting.

Further objects and advantages of the invention will be apparent from the following specification and accompanying drawings in which

Fig. 1 is a front elevation of one embodiment of the invention illustrated as mounted on the front of a panel-board.

Fig. 2 is a side elevation of Fig. 1.

Fig. 3 is a sectional elevation on line 3—3 of Fig. 2.

Fig. 4 is a sectional elevation on line 4—4 of Fig. 1.

Fig. 5 is an elevation, partially in section, illustrating the invention as mounted on the back of a panel-board.

Fig. 6 is a sectional elevation on line 6—6 of Fig. 4.

Fig. 7 is a perspective view of a means for connecting one lead to the rheostat arm.

Fig. 8 is a perspective view of a saddle for attaching the supporting members or legs to the unit, and

Fig. 9 is a perspective view of a terminal block for the lead connections.

In the embodiment of the invention illustrated, the casing consists of a sheet iron plate 1 having an outer rim or flange 2 turned at right angles thereto to form a container-like structure for the resistance elements. The

inner surface of this iron plate contains an insulating material upon which is located the resistance elements connected to a series of circularly arranged contacts 3. The resistance elements are covered with a coating of vitreous enamel, but as this construction of the resistance elements and arrangement of the fixed contacts forms no part of the present invention, it need not be particularly referred to, and other suitable construction may be utilized.

The plate 1 has a central circular opening and the bearing member 4 welded adjacent thereto to form a relatively long center or main bearing for the hollow main shaft 5.

Attached adjacent to one end of the shaft at right angles thereto and rotated therewith, is a drive arm 6. The arm 6 is provided with apertures diametrically opposite the shaft 5 for the two piece insulating spacers 7. The spacers 7 are constructed of insulating material and serve as a supporting means for insulating and attaching the contact member 8 to the metal arm 6. A split rivet 9 passes through an aperture in the contact member 8 and the spacers 7, so as to secure the contact member to the drive arm 6, as clearly shown in Fig. 4.

The contact member is provided with a central circular section 10 spaced from and concentric with the main shaft 5. This contact member is constructed of spring material and is bent over at one end 11 so as to contact with the circularly arranged contacts 3 upon rotation of the shaft 5. The end 11 is rounded back along its sides at 12 in order to provide a smooth contact as it glides over the contacts 3. The fixed connection 13 is attached at one end to the insulating terminal block 14 by means of a screw bolt 15, and makes at its opposite end a rotating contact with the contact member 6. Ring section 16 of the same diameter and width as the circular section 10 of the contact member 6, is provided at the end of the connector 13. This ring section 16 is provided with tabs 17 which are bent inwardly and around the circular section 10 with a spring phosphor bronze washer 18 therebetween in order to insure a perfect rotating contact at all times.

A connection 19 with screw bolt 20, which is threaded to plate 21, provides one of the lead connections. When more than one unit is coupled together, connectors 22 provide electrical connection between units which are held in place by clamps 23 and screws 24 threaded to the plate 21.

The insulating block 14 is bolted to the outer rim or flange 2 of the plate 1 by means of bolts 25 which have heads 26 counter-sunk in apertures 27 said bolts being held in place by nuts 28. These bolts also provide a means for securing stop 29 which has a section 30 protruding in the path of the end of the drive arm 6. The drive arm contacts with this stop on rotation, preventing further movement thereof.

A metal terminal box or fitting 31 surrounds the insulating terminal block 14 straddling the units and having a cover 32 for the lead-in connectors. The terminal box or fitting with its cover is held in position by means of screw bolts 33 threaded into the heads 26 of the screw bolts 25 as shown in Fig. 3. The cables containing the entrance leads for connection to the rheostat units enter the terminal box through inlet 34 of the cover 33 and are then connected to the binding posts.

A back plate 35 for enclosing the rheostat structure fits into the outer rim or flange 2 of the plate 1 and is held in place by means of saddles 36 spaced around the circumference of the flange 2, the plate 1 and the back cover 35 providing an enclosing casing for each unit. The saddles 36 have side flanges 38, 39, 40 and 41. The flange 38 curves to fit the connection between the plate 1 and its flange 2, and the flange 39 is bent at right angles to the body portion to hold the back plate 35 in position. The flanges 40 and 41 are bent at right angles to the body portion providing a channel for the supporting elements or legs 42. A central screw 43' is passed through apertures in the supporting elements 42, the saddles 36 and then threaded to the flange 2 holding the supporting elements to the unit, and, at the same time, securing the saddles 36 for holding the back plate 35; thus forming a totally enclosed rheostat unit.

When two or more units operate together, a fitting 43 passing through an aperture in the back plate 35 is attached by means of a bolt 44 to the shaft 5 of the adjacent unit. Secured to this fitting, within the unit, is an extension 45 having at its end two right angled extensions 46 which straddle the extension 47 struck out from the drive arm 6, making a connection therewith so that rotation of the drive arm will be communicated to the adjacent unit or units as shown in Fig. 4.

The shaft 5 is rotated by means of a handle 48. A fitting 49, with a washer 50 interposed between it and plate 1, is attached to the

shaft 5 by means of a square-headed screw bolt 51. The handle 48 fits over this fitting and is provided with a longitudinal slot for the square head of the screw bolt 51. To secure the handle to the shaft 5, a screw 52 is longitudinally threaded within the shaft 5 with its head in an aperture 53 of the handle. A cover plate 54 serving, if desired, as a name plate, is attached to the handle over the aperture 53, thus covering the attaching screw 52.

The supporting elements or legs 42 are provided at one end with attaching sections 55 which are bolted to the panel-board 56 by means of bolts 57 passing through the sections 55.

In Fig. 5 the rheostat units are shown as mounted on the back of the panel-board. The supporting elements 42 are reversed from the position shown in Figs. 2 and 4 and the unit attached to the back of the board. Fitting 49 is attached to a shaft extension 58 by means of a screw bolt 59. This shaft extension passes through the aperture in the panel-board and the handle 48 is attached thereto in the same manner as explained above.

A bushing 60 may be attached to the panel-board by means of screws 61 if it is desired to carry the handle out from the panel-board.

It is apparent from the above description that the invention provides a construction for a rheostat unit and cooperating means which are adapted to be built up to any extent desired for front or back mounting. The units and their connections are each totally closed as described in the description.

While the invention has been illustrated and described more particularly with reference to one embodiment of the invention, it is not confined thereto, but is intended to cover any other uses or modifications within the scope of the appended claims.

I claim:

1. In a rheostat unit, the combination of resistance elements, a casing supporting and enclosing the resistance elements and having separable front and back portions, supporting elements for supporting said unit from a panel board, and devices interposed between the casing and the supporting elements, said devices having extensions for engaging said front and back portions of said casing for holding them in assembled relation and having extensions for engaging said supporting elements for holding them perpendicular to the casing.

2. In a rheostat unit, the combination of resistance elements, a plate supporting the resistance elements, a back plate for enclosing the resistance elements, supporting elements for supporting said unit from a panel board and devices interposed between said plates and said supporting elements, said devices having extensions for engaging said front and back plates for holding them in assem-

- bled relation and having extensions for also engaging said supporting elements for holding the said supporting elements parallel to each other and perpendicular to the plates.
- 5 3. In a rheostat unit the combination of resistance elements, a plate supporting the resistance elements, said plate having an edge portion turned at right angles thereto, a back plate fitting within the edge portion of the first mentioned plate for enclosing the resistance elements, supporting elements for supporting said unit from a panel-board, saddles interposed between said plates and the supporting elements for aligning said supporting elements and for holding the plates in assembled relation and means passing through said edge portion and saddles for connecting the supporting elements to the unit.
- 10 4. In a rheostat unit the combination of resistance elements, plates supporting the resistance elements and means whereby said plates may be secured together and to the front or back of a panel-board comprising saddle members and supporting elements, said saddle members having extensions for holding said plates in assembled relation and extensions for holding said supporting members perpendicular to said plates.
- 15 5. In a rheostat unit, the combination of a plate having fixed contacts thereon, a shaft, a metal drive arm supported by said shaft, a contact member, an insulating support carried by said drive arm for supporting said contact member and spacing same from said drive arm, said contact member contacting with said fixed contacts and having a circular portion surrounding and spaced from said shaft, and a fixed contacting member in continuous electrical connection with said circular portion.
- 20 6. In a rheostat unit, the combination of a plate having fixed contacts thereon, a shaft, a metal drive arm supported by said shaft, a contact member, an insulating support carried by said drive arm for supporting said contact member and spacing same from said drive arm, said contact member contacting with said fixed contacts and having a circular portion surrounding said shaft, and a fixed contacting member having portions disposed circularly and having electrical connection with and embracing said circular section.
- 25 7. A rheostat unit comprising a plate having fixed contacts thereon, a drive arm, a shaft supporting said drive arm, a contact member carried by and insulated from said drive arm having a circular section, a fixed connector having a circular section with extensions for contacting with the circular section of said contact member and a contact washer interposed between said contact member and said extensions to provide extensive
- 30 8. A plurality of rheostat units spaced apart from each other and each comprising a complete unit having a separately enclosed supporting casing and a centrally operated shaft, a drive arm on each of said shafts, a handle on the shaft of the front unit, and a fitting on the shaft of an adjoining unit extending through the casing of the front unit, said fitting having an extension within the casing of the front unit engaging the drive arm of the front unit.
- 35 9. A rheostat comprising an enclosing casing with a series of contacts, a rotating contact member, a terminal block for the terminals of said rheostat secured to said casing by means of screw bolts passing therethrough, a terminal box enclosing said terminal block and terminals extending from said casing, and screws passing through said terminal box and threaded into the heads of the screw bolts secured to said terminal block providing means for securing the terminal box to the casing.
- 40 10. A plurality of rheostat units each comprising an enclosing casing, a series of contacts and a rotating contact member within each casing, a terminal block for the terminals of each rheostat secured to each casing and a single terminal box for enclosing the entire series of terminal blocks.
- 45 11. A plurality of rheostat units each comprising an enclosing casing, a series of contacts and a rotating contact member within each casing, a terminal block for the terminals of each rheostat secured by screw bolts to each casing, connections between the terminal blocks and a single terminal box for enclosing the terminal blocks and terminal connections of each unit secured to the casing by means of screws threaded into the heads of said screw bolts.
